UNITED STATES PATENT OFFICE.

ARTHUR ERNEST JERRAM AND FRANK BYCROFT KEALL, OF LEICESTER, ENGLAND,
ASSIGNORS TO UNITED SHOE MACHINERY CORPORATION, OF PATERSON, NEW
JERSEY, A CORPORATION OF NEW JERSEY.

EDGE-SETTING MACHINE.

Application filed June 19, 1920, Serial No. 390,146, and in Great Britain July 15, 1919.

This invention relates to control mechanism, and more especially to automatic machinery wherein the relative movement of the work and a tool is controlled automatically as by hydraulic valve mechanism.

The invention will be disclosed as embodied in an edge setting machine of the type disclosed in United States Letters Patent No. 1,078,684, granted on the application of Keall, Gouldbourn and Jerram, but is not to be considered as limited in its application to machines of this type since various features of the invention are capable of other uses.

15 Machines of the general type above referred to comprise a tool and a work support arranged for relative movement (preferably automatic) to cause the point of operation of the tool to be transferred along the work, and a controlling mechanism which acts during the transfer to control or correct automatically as, for example, by feelers, the relative positions of the tool and work in accordance with changes in their relations 20 due to the progress of the operation. The controlling mechanism may comprise gages, feelers, or other contact members, and in the machine shown, is operated by feelers bearing directly upon the work, but it may co- 25 operate with any form or contour or pattern surface having a desired definite relation to the work.

In the machine shown in the above mentioned patent this correcting mechanism 30 comprises a hydraulic piston, the movement of which effects the corrective movements desired, and a main valve controlling the piston, the main valve being operated directly by a work or pattern contact control. On the 35 other hand, the illustrated machine provides a control-operated relay valve for operating the main valve with the advantage that the main valve can be made as rugged and heavy in construction as desired, since it is no longer necessary to move it by the minute 40 control impulses, and the relay valve can be made light and diminutive and therefore exceedingly sensitive to small variations in control-imposed stress.

50 The great sensitiveness produced by this relay valve mechanism brings with it a new but natural difficulty which is found to require correction. The mechanism is so sensitive that it "hunts" continually; that is, the

main work-tool-control piston gets into a 55 state of oscillation, due to minute anomalous impulses delivered to the feelers by roughness on the pattern surface, vibration, and other causes. The invention therefore provides also for the elimination of hunting by insuring 60 that a substantial feeler movement shall be necessary to throw the main correcting piston from one species of its movement to the other. This creates a certain sluggishness of the control mechanism, but does not make it 65 insensitive, in the sense of being unreliable. The parts moved by the feelers are so small that the lightest impulse will move them, but it is necessary to move them a substantial 70 distance before the machine will respond.

This is assisted by providing a member 75 movable to effect desired corrections, but offering a discontinuously variable resistance or tendency to movement at a certain position, so that hunting about this position is avoided. In the machine shown this is accomplished by imposing a discontinuously varying resistance or stress upon a member 80 movable to effect the desired correction. The feeler motion necessary to take up the discontinuity insures that mere adventitious movements of the feelers will not influence the 85 correcting mechanism.

A feature of the invention consists in a member movable to effect corrective changes 90 in the relation between the work and the tool and means for moving the member by means of unbalanced opposing stresses, one of said stresses being discontinuously variable when the member is at a certain position, so that 95 hunting about this position is avoided. In the machine shown the member is a piston valve and the discontinuously varying stress is supplied by springs of varying strengths, arranged to come into operation successively.

These and other features of the invention comprising certain combinations and arrangements of parts will be understood from the following description of a preferred embodiment thereof selected for purposes of 100 illustration and shown in the accompanying drawings in which,

Fig. 1 is a front elevation of the machine with a part of the frame broken away to show the internal construction.

Fig. 2 is a plan view of the machine shown in Fig. 1 with the upper part removed.

Fig. 3 is a side view of a portion of the

machine shown in Fig. 1 drawn to a larger scale, with certain parts in section.

Fig. 4 is a vertical section showing in detail the tool carrying head.

5 Fig. 5 is a plan partly in section of the parts shown in Fig. 4.

Fig. 6 is a front elevation showing certain details of the feeler mechanism.

Figs. 7, 8 and 9 show in three positions 10 the valves which control the supply of fluid to the correcting hydraulic cylinders, the casting being tipped over from its normal vertical position in the machine, with the parts at the right of these figures at the lower end.

15 Fig. 10 is a perspective of the tool carrying head.

Fig. 11 shows the mechanism for bringing the jack to normal work inserting position, and

20 Fig. 12 is a similar view of a modified form of valve.

Only enough of the machine is described in detail to enable the invention to be understood. For a fuller description of parts not 25 material to the present invention, reference is to be made to Patent No. 1,078,684, above mentioned.

In this specification it is to be understood that by the path of relative traverse of the 30 tool is meant that path in which, during the relative motion of the tool and work, the tool is in active operation on the work; and it is contemplated that this path may be shorter than the extent of relative movement 35 of the tool and work, since these members may be so controlled as to move clear of each other before the relative motion of tool and work has ceased.

The machine comprises a jack or work support upon which the boot or shoe is securely held and an edge setting tool that has rapid vibratory movements of small amplitude imparted to it to burnish the sole edge of the shoe with which it is maintained in engagement.

45 The jack comprises a frame 2 of a laterally-disposed U shape on the lower arm of which is a dove-tailed slideway 4 that supports an adjustable block 6 for engaging and positioning the tread face of the sole of the shoe; this block may be adjusted longitudinally of the shoe along the slideway and be retained in its adjusted position by any suitable means such as a spring plunger 8 so located in the 55 frame as to engage suitably shaped recesses in the block 6. Toward the bend of the U-shaped frame there is an adjustable, vertically-disposed rest 10 for the tread face of the heel of the shoe.

60 A U-shaped clamp 12 adapted to embrace the counter portion of the shoe so as to position it centrally in the jack is adjustably mounted in the bend of the frame.

65 The shoe is held upon the jack by a pendant clamp member 14 carried in the upper

arm of the frame and operated by the handle 20 so as to engage the shoe and hold it firmly in the jack. A more detailed description of this clamp is not necessary to the disclosure of the present invention but it will be found, 70 if desired, in Patent No. 1,078,684, above referred to.

The jack and tool are moved relatively by automatic mechanism to transfer the point of operation of the tool around the sole edge, 75 and mechanism, controlled by feelers bearing upon the sole edge and by feelers bearing upon the tread face of the sole near its edge, imparts the relative angular movements between the shoe and tool that are necessary to insure that the acting face of the tool shall bear evenly upon every part of the sole edge upon which it operates.

The jack 2 is secured upon the upper end of a vertical spindle 42 journaled in bearings at 80 one end of a frame 44 of which the other end is pivotally carried at 46 (see Fig. 2) upon a second frame 48 that swings about a vertical spindle 50 supported in the machine frame. The two frames 44 and 48 in their 85 mean position are disposed approximately at right angles to each other so as to permit horizontal movements of the jack in any direction.

A lobed cam 52 fixed to the lower end of 90 the spindle 42 has a cam groove formed in it which engages two rollers 54, 54 which are supported in a manner hereinafter described. The cam and rollers so guide the jack during 95 its movement that the sole edge of the shoe on the jack moves past the tool in a path agreeing approximately in shape with the 100 contour of the sole edge, or in a path that is the mean of a variety of contours of shoe soles; the relative traverse of the tool and sole edge being brought into exact agreement 105 with the contour of the shoe under operation by the horizontal and vertical movements which are imparted to the jack and tool respectively by the feeler mechanism.

The mechanism for driving the jack 2 comprises a slide 56 that is mounted to reciprocate in guideways 58 and 60 attached to or formed upon the machine frame. The slide 56 is coupled by a piston rod 62 to the piston 64 of a hydraulic cylinder 66 secured to the machine. Motion is transmitted from the slide 56 to the jack by means of two chains or other similar flexible members 68 and 70. The chain 68 is secured to the slide 56 at one 110 end and after passing around pulleys 72, 74 and 76 is attached at its other end at 78 to the cam 52; and the chain 70 also secured to the slide 56, passes around pulleys 80, 82, 84, 86, 88, as shown in Figs. 2 and 3, and is joined to the cam at 90. To increase the motion derived from the slide 56 the pulleys 74 and 82 are mounted upon the slide while the remaining pulleys, except 84, are carried upon the machine frame. The pulley 84 is 120 125 130

carried upon a lever 92 pivoted to the machine frame and is acted upon by a spring 94 to keep the chains 68 and 70 under the necessary tension. If desired, the 5 chains instead of being attached to the cam 52 may be secured to a pulley of corresponding formation.

By the connections above described, the 10 jack is oscillated from side to side by the reciprocal motion of the slide 56 and the direction of motion of the slide is reversed automatically by a mechanism not necessary to be described here, a full description of which will be found in Patent No. 1,078,684, already referred to. This mechanism operates the 15 valve 102 that controls the supply of fluid to both sides of the piston 64 in the hydraulic cylinder 66 before mentioned.

The point of operation of the tool is transferred along the sole edge of the shoe, from 20 the shank on one side of the sole, around the toe portion, to the shank on the other side of the sole; the direction of motion of the jack being reversed when the tool reaches the 25 shank.

The edge setting tool 200 (Fig. 4) has an 30 acting face 202 to engage the sole edge and is provided with a lip to engage the underside of the sole edge. The upper side of the 35 sole edge preferably is engaged by a stitch wheeling disk 204 that is pivoted upon the tool.

The tool is movably mounted in a holder 40 206 so that it may turn freely about the center 207 in a vertical plane transverse to the end of the shoe. The shank 208 of the holder 206 is slidingly keyed in a T-shaped piece 210 (Figs. 4 and 5) having a vertically extending stem 211 fulcrumed in a bushing 213 in an extension 212 from a sleeve 214 that is 45 rotatably mounted at 215 in a bearing frame 216 supported by pivots 218 which couple it to two pairs of twin levers 220, 222. The twin levers 220 are pivoted upon a frame 50 lever 224 pivoted at 226 (Fig. 1) upon the machine frame. The twin levers 222 are connected to the frame lever 224 by a bell crank 55 lever 228 pivoted at 230 to the frame lever 224. The other end of the bell crank lever 228 is coupled to a projection from the machine frame by means of an anchor link 232. By this construction the tool holder 206 can 60 be vibrated laterally about the fulcrum 211 of the T-shaped piece 210; the sleeve 214 and tool holder 206 can be angled about the common axis of the shank 208 and of the sleeve 214; while the sleeve 214, tool holder 206 and bearing frame 216 during their lateral and vertical movements to follow the sole 65 edge are maintained horizontal by the action of the twin links 220, 222 which, in conjunction with the bell crank 228 and link 232 constitute a parallel motion device.

The edge setting tool 200 is vibrated rapidly 70 about the axis of the stem 211 by connec-

tions from a shaft 234. This shaft may be oscillated by any suitable mechanism but preferably by a mechanism of the type described in the specification of U. S. Patent No. 1,035,445, granted Aug. 13, 1912. This mechanism is indicated at 236, Fig. 1, and is not herein described as it, in itself, forms no part of the present invention. The mechanism may be conveniently operated from the pulley 348 (Figs. 1 and 3). The shaft 234 is connected with the tool holder 206 by a universal coupling comprising a sleeve 238 (Figs. 4, 5 and 10) open at the top, as at 239 (Fig. 5) to admit the member 210 (the ends of the sleeve being pivoted upon the shank 208 outside the member 210) and a fork 240 that is secured to the shaft 234 and is pivotally connected with the sleeve 238 by a pin 241 disposed at right angles to the shank of the tool holder. The member 238 constitutes the cross-shaped 80 member of the universal joint between the shaft 234 and the stem 211.

Backward thrust of the tool owing to its pressure upon the work is transmitted to the bearing frame 216 by a thrust rod 242 seated 85 at one end against a set screw 244 screwed into the frame 216, its other end engaging the bottom of a recess in the shank 208 of the tool holder 206, the point of engagement being located at a point in the axis of the 90 T-shaped piece 210.

The tool 200 is pressed against the sole edge of the shoe by means of a spring 248 (Figs. 1 and 3); and by the co-operation of this spring with the cam 52 on the lower end of the spindle 42 of the jack 2 the point of operation of the tool is caused to travel along the sole edge during the movement of the jack. But it is necessary during the movement of the jack that there be angular movement in a horizontal plane between the jack and the tool to maintain always the acting face of the tool in proper engagement with the sole edge at every part of the contour thereof. Further, it is necessary also that the jack and tool be turned relatively about an axis that is normal to the acting face 202 of the tool owing to the fact that all parts of the sole do not lie in the same plane. These movements of adjustment between the jack 110 and the tool are effected automatically by the correcting devices hereinafter described.

The correcting device for angling the jack in a horizontal plane in relation to the tool 115 comprises a hydraulic cylinder 248 (Fig. 2), the piston rod of which is connected by a link to a jack correcting lever 250 pivoted at 252 to the machine frame. This lever supports the two rollers 54, 54 hereinbefore referred to as engaging the groove in the cam 52 on the lower end of the jack spindle. The valve 254 (Fig. 1) of the hydraulic cylinder is controlled by two feelers 256, 258 (Figs. 5 and 6) which, under the action of suitable springs, 120 bear upon the sole edge, one on each side of 125

the edge setting tool 200. The feeler 256 is coupled to one end of a lever 260 pivoted upon an extension from the sleeve 214 and the feeler 258 is coupled to a lever 262 also pivoted 5 upon the sleeve 214. The lower ends of the levers 260, 262 are connected by a cross bar 264 (see Fig. 6) which constitutes one element of a universal joint connected to the upper end of a shaft 266 having at its lower end a similar 10 joint with the spindle of the valve 254 (Fig. 1). The operation of this correcting device is as follows:—When the tool is bearing evenly upon the sole edge, the valve 254 of the cylinder is maintained closed by the connections between it and the feelers 256, 258. 15 But when the feelers are moved relatively to one another by changes in the contour or general direction of the sole edge passing the tool, the levers 260, 262 to which the feelers 20 are coupled will likewise be moved relatively, thus angling the cross bar 264 that joins them and transmitting motion, by partial rotation of the shaft 266, to the valve 254. The valve being thus actuated causes the piston of the 25 cylinder 248 to be set in motion so that the jack correcting lever 250 is turned upon its pivot 252. The jack 2 being connected to the lever 250 by the rollers 54, 54 and the cam 52 will also be swung about the pivot 252 of the 30 lever 250 as a center until the sole edge of the shoe on the jack is returned by such movement to the position in which the tool bears evenly upon it, by which time the feelers 256, 258 will likewise be restored by the movement 35 of the sole edge to their initial position and they will close the valve 254 and stop the motion of the piston and of the parts connected therewith.

The correcting device that effects a relative turning movement of jack and tool about an axis that is normal to the acting face of the tool comprises a hydraulic cylinder 270 (Fig. 3) the piston of which is connected by a thrust rod 272 (Figs. 3 and 10) with an extension 274 from a collar that is secured to the projection 212 from the sleeve 214. A spring 276 (Fig. 4) connects the sleeve 214 and the bearing frame 216 and opposes the thrust of the rod 272. The valve 278 (Fig. 1) that regulates the admission of fluid to the cylinder 270, is controlled by two feelers 280, 282 (Fig. 5) that bear upon the tread face of the sole of the shoe immediately adjacent to the sole edge. These feelers are formed as spring sustained levers pivoted upon extensions from the sleeve 214, the free ends of the levers being coupled by a cross bar 284 (Fig. 4) connected by a universal coupling and a shaft 286, with the rotary valve stem of the cylinder 270. 50 The action of this correcting device is similar to that first mentioned, that is to say the feelers 280, 282 being displaced relatively by changes in the contour of the portion of the sole engaged by them, angle the cross bar 284 55 and turn the valve 278 so that the latter is

actuated either to cause the piston of the cylinder 270 to be raised by the admission of fluid or to permit it to be depressed by the action of the spring 276 on the sleeve 214. The sleeve, tool holder and tool are thus 70 turned about the axis of the shank of the latter to restore the sole edge and tool to their original relationship, namely one in which the plane of vibration of the tool coincides with that of the part of the sole edge 75 engaged by it. The angling of the sleeve 214 causes the feelers 280, 282 bearing on the sole to be returned to their normal position, thus again actuating the valve stem 278 and stopping the motion of the piston. 80

It may here be remarked that in order to permit movement of both sets of feelers toward and away from the valves controlled by them as the feelers follow the traverse of the tool, or as the tool carrying head is moved 85 bodily toward and from the work, the shafts 266 and 286 preferably are made telescopic and with pin and slot connections (see Figs. 1 and 3) so that turning movements only are transmitted to the valve. The shaft 234 90 which imparts vibratory movement to the tool is also made telescopic as shown in Fig. 1 to permit the movements of the tool hereinbefore indicated.

To move the tool into engagement with the sole edge or to remove it therefrom, a starting and stopping lever or controlling lever 290 is provided which is fixed upon a rockshaft 292 journaled in the machine frame. The rockshaft 292 has upon it an arm 294 to which 100 is pivotally linked a plunger 296 into which extends a rod 298 free to turn within a bearing upon the frame lever. The spring 246, the function of which is to keep the tool pressed against the sole edge while the machine is in operation, surrounds the rod 298 and abuts at its lower end against a collar 300 supported by projections from a nut 302 working on a screwed portion of the rod 298 and at its upper end against an abutment 304 105 pivoted on the lever 224. A collar 306 secured to the upper end of the rod 298 operates to limit the movement of the rod in the abutment 304 under the influence of the spring 246. By this construction the tool can be moved yieldingly toward the sole edge and removed positively therefrom. Preferably the plunger 296 works in a dash pot 308 which cushions the movement of the lever 290 and arm 294 when the machine is thrown automatically out of action. 110

A pump 360 (Fig. 2) is provided which supplies fluid, such as oil, under the requisite pressure to the hydraulic cylinders of the machine and there is an air pressure chamber 362 (Figs. 2 and 3) into which the fluid is pumped before passing to the hydraulic cylinders. 115

The valve mechanism for operating the automatic correcting devices is contained in 120 125 130

a casing 370 (Figs. 1, 7, 8 and 9). This casing contains both of the control valves for the mechanisms for angling the jack in a horizontal plane and rocking the tool about a horizontal axis. A description of the former of these mechanisms will suffice inasmuch as they are quite similar. The casing 370 contains a cylindrical bore 372 (Fig. 8) enlarged at its bottom as shown at 374 (at the right in Fig. 8) to provide a shoulder 375 and containing the main piston valve 376. This valve is of the balanced or equilibrium type and is reduced as shown at 378, 380, 382, the remaining portions 379, 381, 383, 385 fitting the bore 372 accurately. The lower end of the piston valve 376 is chambered as at 384 to accommodate a spring 386, one end of which rests against the piston and the other end against a disk 388 in the bore 374. The diameter of this disk is larger than the diameter of the main body of the bore 372 so that it can rest against shoulder 375 at the place where the bore changes size. Below the disk is a spring 392 substantially stiffer than the spring 386, one end of which rests against the disk and the other against the bottom of the casing 370. Thus the resistance offered to movement of the piston varies irregularly or discontinuously when the spring 386 has been fully compressed and as the compression of spring 392 is commenced. A pin 394 is fixed in the piston 376 and serves to guide the springs and the disk, and extends outside the casing for a purpose to be described below. One side of the casing has two ports 396, 398 from which pipes lead to the ends of the cylinder 248 (Fig. 2) to operate the piston therein. These ports are spaced to coact with the valve portions 381, 383. The other side of the casing has three ports 400, 402, 404 connected to the pump 360. When the piston 376 is in the position shown in Fig. 7, oil from the pump 360 enters the port 402, passes around the reduced portion 380 and into the port 396, operating the piston in the cylinder 248. The oil on the other side of the piston in the cylinder exhausts through the port 398 around the reduced portion 382 and out of the port 404 to the pump 360. When the piston 376 is in the position shown in Fig. 9, oil from the pump enters through the port 402, passes around the reduced portion 380 and out of the port 398 to operate the piston in the cylinder 248 in the other direction. The oil on the other side of the piston in the cylinder exhausts through the port 396, passes around the reduced portion 378 and returns to the pump through the port 400. When the main piston is in the position shown in Fig. 8, both the ports 396 and 398 are closed and the piston in the controlling cylinder 248 is held motionless.

The main valve piston 376 is operated by the following described mechanism. The shaft 266 passes into the casing 370 and carries a lug 406 extending laterally from it. A small dog 408 is pivoted at 410 upon the casing 370 in position to be swung by contact of the lug 406 with one side of it as the shaft 266 is turned through a small arc. Its other side engages a small plunger 412 sliding in a guide in the casing 370. This plunger has a reduced end of peculiar formation. The tip end is conical as shown at 414. Behind this conical end is a reduced cylindrical portion 416 which is joined to the main body of the plunger by another conical portion 418. The end is arranged to move in and out of a port 420 in the casing which extends between a chamber 422 leading to an outlet pipe 424 and a recess or pressure chamber 426 formed in the top of the cylindrical bore 372. A very small inlet pipe 428 communicates with this recess, so that the pressure in the chamber depends on the extent of opening of the port 420.

Suppose the parts are in the Fig. 7 position and that the feelers which control the shaft 266 are operated in such a way as to move the valve piston 376 from this extreme position. The feelers will turn the shaft 266 in valve casing 370 so as to force the plunger 412 to the right in Fig. 7, thereby reducing the effective area of the aperture 420. This causes the pressure in the chamber 426 to increase, as the fluid is pumped in through the inlet pipe 428. When the pressure increases sufficiently the piston 376 will move to the right compressing the spring 386 until the end of the piston seats upon the disk 388. At this point the ports at 396 and 398 (Fig. 8) will be closed, the cylindrical portion 416 will just be entering the port 420, and the control piston in the cylinder 248 will be locked. It will not yet have begun any reverse movement, but if it was moving at the time the plunger 412 began to move, its movement in that direction will gradually have stopped. Further movement of the piston 376 cannot occur until the pressure in the chamber 426 has increased abruptly a substantial amount equivalent to the (substantial) difference in the pressures exerted by the springs 386 and 392. The major part of this increase in pressure will occur after the cylindrical portion 416 of the plunger has passed into the port 420. The purpose of this cylindrical portion is to necessitate an appreciable movement of the feelers in raising the pressure in the chamber 426 to the required degree so that the pressure in the pressure chamber is an increasing but discontinuous function of the position of the piston, reckoned from one extreme to the other of the movement of the piston. The pressure having reached the required point, the disk 388 moves back against the spring 392, compressing it until the parts reach the position shown in Fig. 9 at which time the ports at 396 and 398 will have been uncovered.

and the oil will pass through them in the direction opposite to that in which it was passing at the beginning of the described cycle, and the correcting movement initiated by the movement of the feelers will take place.

The behavior of the apparatus is quite similar in moving in the opposite direction. As the pressure in the chamber 426 drops 10 due to the action of the feelers in allowing the valve 412 to open, the piston 376 moves to the left in Fig. 9 until the spring 392 has seated the disk 388 on the shoulder 375, and the pressure is then permitted to drop a substantial degree after a substantial movement of the plunger 412, before the piston 376 begins to move again.

The mechanism described, comprising the two springs and the cylindrical portion of the 20 plunger 416 will thus cause a certain slight sluggishness in response to the feeler movement, but will entirely prevent hunting inasmuch as a substantial difference in pressure in the chamber 426, which means a substantial movement of the feelers, is necessary 25 in order to change the control from one phase to the other. The plunger 412 and its operating parts can be made very small and light in weight since the aperture 420 need not be 30 at all large and therefore the response of the plunger to the reaction between the work and the feelers is practically instantaneous. At the same time, the main valve structure, comprising the piston 376 and its related parts, 35 can be made as heavy and rugged as is found necessary, instead of being governed in construction by the force exertable by the feelers which ultimately control it, as would be the case if the feelers operated upon it directly. The force which operates the main 40 valve piston 376 is the pressure of springs acting to lift the piston and the pressure in the chamber 426 and the adjoining part of the bore 372 above the piston acting to depress the piston toward the right in Figs. 7, 8 and 9. This pressure may be varied by the additional or subtractional flow of a small quantity 45 of fluid and this flow may take place at any desired part of the chamber. Therefore the plunger 412 may be located as conveniently 50 as desired to the feelers while the main valve piston may be located elsewhere in the machine where it will be out of the way. The chamber 426, of course, may be reduced to a small pipe connecting the bore 372 with the aperture 420, all that is necessary being a 55 means of transmitting hydrostatic pressure to the piston 376.

The mechanism for maintaining the jack 60 in convenient position for the insertion of new work will now be described.

On the jack correcting lever 250 (Fig. 2) is fast an upstanding arm 430 (Fig. 11) pivoted to which on a horizontal pivot 432 is a 65 second arm 434 having a cam 436 on its upper

surface immediately below the lower end of the pin 394 (see also Figs. 7 and 8). The end of this arm 434 rests upon and is supported by one end of a lever 438 pivoted between its ends on a horizontal pivot 440 at one end of a vertically disposed bell crank 442 pivoted 70 to the frame of the machine at 444 and the remaining end of which is connected by a third horizontal pivot 446 to one end of a rod 448 the opposite end of which is threaded into a nut 450 held from endwise movement in the frame of the machine and provided with an enlarged knurled head easily accessible to the operator. The other end of the lever 438 is bent downwardly at 452 and held in contact 75 with the frame of the machine by a tension spring 454.

A projection 456 from the lever 438 on the same side of its fulcrum as the downwardly bent end 452 is in the path of a push rod 458 85 pivotally connected to a crank arm 460 on the starting shaft 292 to rise as the starting lever finishes its travel in the starting operation and move the lever 438 to allow the arm 434 and its cam surface 436 to fall, thereby 90 releasing the piston valve to the control of the relay valve and feelers.

Movement of the jack in that direction in which leakage through the valve system tends to move the jack when the tool head is in inoperative position will be accompanied by corresponding movement of the jack correcting lever 250. The arm 434 will move in company with it and the cam surface 436 (Fig. 7) is so formed that when moving in such a direction it will act on the pin 394 100 to move the piston member 376 in a direction to cause movement of the jack in the sense opposite to that in which leakage tends to move it. Consequently these opposing influences establish a balance determining a definite position of the jack notwithstanding leakage, which position may be readily varied by rotation of the knurled head 450 aforementioned which moves the bell crank about 105 its fulcrum and raises or lowers the fulcrum 440 of the lever 438 which it supports and the downwardly bent end 452 of which is definitely positioned by the frame.

The mechanism above described is entirely 115 automatic, independently of leakage in the piston valve, since a position of the jack-correcting lever 250 other than that for which the machine is set will cause a movement of the pin 394 in a direction to move the jack 120 correcting lever 250 back to the normal position. It may, however, be sometimes regarded as desirable to set the valve to leak definitely in one direction (and the apparatus 125 will normally wear into this condition irrespective of manufacturing intent), as for example, by making the cylinders 381, 383 slightly conical in the same direction, say, with the apices of the cones to the right in Fig. 8 as shown, much exaggerated, in Fig. 130

12. The piston 376 would then be shifted to the right in Fig. 8, by the dropping of the pin 394 along the cam 436 until the port 398 barely opened as in Fig. 9 so that the tendency 5 to leak would just be balanced.

The automatic jack control mechanism above described is not claimed herein since it constitutes the subject-matter of Patent No. 1,472,071, granted October 30, 1923, upon the 10 application of Frank B. Keall.

Having described our invention, what we claim as new and desire to secure by Letters Patent of the United States is:—

1. A fluid control mechanism comprising a cylinder having ports, a piston valve arranged to slide in said cylinder to control said ports, a pressure chamber in communication with one end of the cylinder to provide pressure for moving the piston valve, a spring to 15 oppose such movement of the piston, an inlet port for said chamber, an outlet port, a slideable needle valve for controlling said outlet port and adjusting the pressure in the chamber, said needle valve comprising a plunger 20 having a portion of substantially uniform cross-section movable out of and into said outlet port and another portion of rapidly increasing cross-section arranged to be moved into said outlet port thereby to decrease its 25 effective opening more than can be accomplished by the portion of uniform cross-section, and automatically operated means for sliding said needle valve to the desired position.

35 2. A fluid control mechanism comprising a cylinder, a piston control valve arranged to slide in said cylinder, a pressure chamber in communication with one end of the cylinder to provide pressure for moving the piston, a resisting mechanism to oppose such movement of the piston, an inlet port for 40 said chamber, a cylindrical outlet port, and a needle valve for controlling said outlet port and adjusting the pressure in the chamber, comprising a plunger having a conical portion and a cylindrical portion movable out of and into said port, said portions being arranged to enter said port successively, whereby after the plunger has moved a certain distance to cause the cylindrical portion to enter the port and the pressure in the chamber has risen correspondingly, a substantial further movement of the plunger will cause no substantial further increase in pressure.

55 3. A fluid control mechanism comprising a cylinder, a piston control valve arranged to slide in said cylinder, a pressure chamber in communication with one end of the cylinder to provide pressure for moving the piston, a resisting mechanism to oppose such movement of the piston, an inlet port for said 60 chamber, a cylindrical outlet port, and a relay needle valve for controlling said outlet

port and adjusting the pressure in the chamber, comprising a plunger having a conical portion, an intermediate cylindrical portion, and a second conical portion, said portions being arranged in order along it to enter said port successively, whereby after the plunger has moved a certain distance and the pressure 70 in the chamber has risen correspondingly, a substantial further movement of the plunger will cause no substantial further increase in pressure, and a still further movement of the plunger will cause the pressure to continue 75 increasing.

4. A fluid control mechanism comprising a cylinder having ports, a piston control valve arranged to slide in said cylinder to control said ports, a pressure chamber in communication with one end of the cylinder to provide pressure for moving the piston, a resisting mechanism to oppose such movement of the piston, said mechanism comprising a plurality of springs arranged in series to engage 80 said piston, said springs having substantially different characteristics, so that the force exerted by the springs against the piston undergoes an abrupt change at an intermediate point in the range of movement of the piston, an inlet port for said chamber, an outlet port, and a needle valve for controlling said outlet port and adjusting the pressure in the chamber.

5. A fluid control mechanism comprising 95 a cylinder having a central bore and enlarged end chambers, a piston valve arranged to slide in said central bore, one of said chambers constituting a pressure chamber in communication with one end of the cylinder, a needle valve for controlling the pressure in the pressure chamber, a spring having one end resting against the piston, a member having a dimension greater than the diameter of the cylinder against which the other end of the spring is seated, said member being positioned in said other end chamber, and a stiffer spring tending to force said member against the end of the portion of the cylinder containing said central bore.

100 6. A hydraulic valve mechanism comprising a piston valve having a socket in one end, a movable end wall for the piston cylinder, a spring seated in the socket and resting against the movable wall, said piston contacting firmly with said wall after the spring has been compressed to the depth of the socket, and a second spring having substantially different characteristics from said first-named spring tending to hold said wall in 105 contact with the end of the cylinder.

In testimony whereof we have signed our names to this specification.

ARTHUR ERNEST JERRAM.
